138,343

DESIGN FOR A COMBINED SALT AND PEPPER SHAKER

Anthony Granese, Blackwood Terrace, N. J.

Application March 15, 1944, Serial No. 112,910

Term of patent 14 years

(Cl. D44—22)

To all whom it may concern:

Be it known that I, Anthony Granese, a citizen of the United States of America, residing at Blackwood Terrace, county of Gloucester, and State of New Jersey, have invented a new, original, and ornamental design for a Combined Salt and Pepper Shaker, of which the following is a specification, reference being had to the accompanying drawing, forming a part thereof, wherein the figure is a perspective view of a combined salt and pepper shaker, showing my new design.

I claim:

The ornamental design for a combined salt and pepper shaker, as shown.

ANTHONY GRANES.
